UNITED STATES PATENT OFFICE.

CLIFFORD A. CUTLER, OF BUFFALO, NEW YORK.

DRYING KILN.

Application filed December 27, 1920. Serial No. 433,307.

To all whom it may concern:

Be it known that I, CLIFFORD A. CUTLER, a citizen of the United States of America, and a resident of the city of Buffalo, county 5 of Erie, and State of New York, have invented certain new and useful Improvements in Drying Kilns, of which the following is a full, clear, and exact description.

It is well known to those skilled in the 10 art, that in order to properly dry any product or material in the least possible time, it is necessary that the temperature and humidity conditions of the drying medium, best suited to the drying of the product or 15 material, be secured and maintained at all points within the drying chamber. Moreover, it is known that such conditions can be secured and maintained only by providing a very rapid, properly directed, and even 20 movement of the drying medium everywhere within the kiln.

The principle object of my invention has been, therefore, to provide a kiln which shall embody the above advantages, and by 25 which materials may be evenly and economically dried in the shortest possible time, and in such a manner as to preserve the quality of the materials.

Another object has been to provide a kiln 30 which shall be simple to manufacture, having combined means for heating, humidifying, de-humidifying and purifying the drying medium.

Another object has been to provide a 35 kiln in which the foul gases or fumes coming from the product or material being dried shall be taken out of the drying medium, without losing any appreciable amount of the drying medium, and preventing any retardation of the drying process.

Another object has been to provide a kiln which shall be so simple in its construction that it may be easily and quickly installed, and one in which repairs or replacement 45 may be easily made.

The above objects and advantages have been accomplished by the device shown in the accompanying drawings in which I have shown my device as applied to the drying 50 of lumber, it being obvious that it may be advantageously used for drying various vegetable, animal, mineral, or chemical products. In the drawings:

Fig. 1 shows a side, sectional elevation of 55 one form of my device and is taken on line 1-1 of Fig. 3, for convenience of illus-

tration, a portion of the kiln being omitted as indicated by the broken lines.

Fig. 2 is a sectional view thereof and is taken on line 2-2 of Fig. 1. 60

Fig. 3 is a sectional, plan view taken on line 3-3 of Fig. 1.

Fig. 4 is an end, sectional elevation of a modified form of kiln.

Fig. 5 is a fragmentary, plan view of the 65 form shown in Fig. 4.

Fig. 6 shows another form of my invention.

Fig. 7 is an end, sectional, view of a modified 70 form of kiln.

Fig. 8 is a reduced, sectional, plan view of the form shown in Fig. 7.

Referring particularly to Figs. 1 to 3, inclusive, my kiln comprises two side walls

10, a rear end wall 11 and a front end wall 12. 75

13 is the roof of the kiln, and 14 is the floor thereof. Arranged on each side of a

central space 15 is a delivery duct 16, each 80 duct being separated from the space 15 by

means of a duct wall 17. A return duct 18 is arranged at one side of each of the de- 85

livery ducts 16 and a duct wall 19 separates each of these ducts from the ducts 16. A

duct wall 20 is arranged at the outside of 90

each of the ducts 18 and in spaced relation with the wall 10. Between each of the duct

walls 20 and the side walls 10 is provided a 95

fresh air duct 21. The central space 15, and the delivery ducts 16 and return ducts

18 extend the entire length of the kiln and 100

terminate at the rear wall 11 and front wall 12. The fresh air ducts extend from the

rear wall 11 and pass through the front wall 12 where each terminates in a pit 22, each of

which is open to the atmosphere. The ducts 105

16, 18 and 21 are enclosed by means of duct

covers 23, which are disposed over the duct 110

walls 17, 19 and 20 and extend from the walls

17 to the side walls 10. The duct covers 23

form a false floor for the kiln, and upon 115

it are suitably supported two pairs of T-

shaped rails or tracks 24. These tracks ex- 120

tend through the front wall 12, which is

A baffle plate or curtain 27 is suspended from the roof 13 of the kiln and extends down in front of the opposite side faces of the two stacks of lumber, thus preventing 5 the currents of air, which come up between the stacks of lumber, from passing over the top thereof, as hereinafter described.

A plurality of openings 30 are provided at suitable intervals throughout the length 10 of the duct walls 17. These openings connect the delivery ducts 16 with the central space 15. Deflectors 31 control the effective size of the openings 30. These deflectors are arranged in front of the openings 15 and extend preferably into the delivery ducts 16, thus serving to apportion the amount of drying medium which is admitted to each of the openings 30. The deflectors 31 are preferably adjusted so as to 20 evenly distribute the flow of air through the openings 30. Arranged in the central space 15 and disposed in front of each of the openings 30 is a radiator 32, which provides means for heating the drying medium as it 25 comes from the openings 30 and before it is passed through the material being dried. A plurality of ports 33 are provided through each of the duct covers 23 and communicate with the space 47 at the lateral, outside surfaces of the piles of lumber 30. These ports 33 are graduated in size and are disposed in a manner opposite to the arrangement of the effective areas of the openings 30, i. e., the largest port 33 is at 35 the end of the duct which is farthest from the blower 34, while the smallest port is at the end nearest the blower.

48 is an operating room which is adjacent the rear wall 11 and in which the blowers 40 34 are located. The suction side of each of these blowers is connected with one of the return ducts 18, and the discharge side of each is connected with one of the delivery ducts 16. The blowers are preferably 45 mounted on or attached to a single shaft 35, whereby they may be conveniently driven by a motor 36. 37 is the steam supply line which is connected with the two series of radiators 32 by means of suitable piping 38. 50 A hand-controlled valve 39 and a thermostatically controlled valve 40 are arranged in the pipe line 38. 41 is the recording thermometer bulb, and 42 is the thermostatic regulator bulb for recording and controlling, respectively, the temperature within 55 the kiln. 43 is a steam pipe which extends into each of the return ducts 18, preferably close to the blower end thereof, and 44 is an open T-fitting. This pipe 43 is 60 connected with the steam line 37 by means of piping 45 and a hand-controlled valve 46, by means of which the humidity of the drying medium may be easily controlled. Suitable steam traps are, of course, provided for taking care of the condensation 65

occurring in the radiators 32, as well as in the steam pipe lines 43.

Arranged at each side of the kiln and extending the length thereof is a curtain wall or porous de-humidifier 50. These de-humidifiers are suspended from the roof 13 of the kiln so that the lower edge of each will terminate at a point immediately above each of the duct walls 20. A plurality of ports 51 are provided through each of the 70 duct covers immediately above the fresh air ducts 21. These ports connect the fresh air duct with the fresh air passageway 52, provided between each of the outer walls 10 of the kiln and the de-humidifiers 50. A plurality of stacks 53 is provided on the roof 80 of the kiln which are so arranged as to communicate with the fresh air passageways 52, whereby a draft of fresh air is created through the passageways 52 and the fresh 85 air ducts 21.

Referring now to the form of device shown in Figs. 4 and 5, 56 are the stacks of lumber which are placed upon trucks 57 supported on tracks 58, suitably arranged some distance above the floor line 59 of the kiln. 60 are the side walls and 61 the roof of the kiln. This structure is very similar to the one hereinbefore described except that the discharge ducts 62, the return ducts 63 and the fresh air ducts 64 are preferably made of metal and placed upon the floor of the kiln. The discharge ducts 62 are provided with ports 65, in front of each of which a radiator 66 is located. Each of the return ducts 63 is provided with ports 67 along its upper face. Each fresh air duct 64 is arranged adjacent a return duct 63, and it is also provided with ports 68 for the passage of fresh air. The fresh air ducts 64 preferably open into the atmosphere through one of the end walls of the kiln. 69 are the porous de-humidifiers of the device, each of which is supported from the ceiling 61 and is suspended immediately over the middle partition of each pair of ducts 63 and 64. The openings 67 and 68 in the ducts 63 and 64, respectively, are thereby separated. The de-humidifier forms a fresh air passageway 70 at the upper end of each of which is provided a suitable ventilator 71, for creating a draft of air through the passageway 70. 110

72 are the blowers, the suction side of each of which is attached to one of the return ducts 63, and the delivery side of each of which is attached to one of the delivery ducts 62. A separate motor 73 is preferably provided for each of the blowers. A steam pipe 74 with a hand controlled valve 75 is preferably attached to the suction side of each of the blowers, and provides means whereby the drying medium will be properly humidified. Suitable steam supply piping 76, and suitable exhaust steam pip- 115 120 125 130

ing 77 are provided for the steam radiators 66. Concave deflecting plates 78 are arranged at the center of the kiln and serve to direct the drying medium upwardly into the central space between the piles of lumber.

In the form of the device shown in Fig. 6, 80 are the fresh air ducts which are separated from the interior of the kiln by 10 means of the porous de-humidifiers 81. 82 are the return ducts, which are connected to the suction side of the blowers 83. Each of these ducts is provided with a plurality of openings 84 in its upper wall. 85 is the 15 delivery duct which is centrally arranged between the piles of lumber 86 and is provided with a plurality of openings 87. The blowers 83 are preferably connected together and driven by a motor 88. The discharge pipes of these blowers are connected together and to the delivery duct 85.

In Figs. 7 and 8, I show a form of my invention in which the discharge and return ducts have been omitted. In these figures, 90 25 are the fresh air passageways which are provided by the outer walls 91 of the kiln and the porous de-humidifiers 92. Regulatable openings 93 are arranged through the walls 91 near the floor line for admitting fresh 30 air to the passageways 90, and openings 94 are arranged through the walls near the top of the kiln for creating a circulation of fresh air through the passageways 90. The piles of lumber 95 are arranged some distance 35 above the floor of the kiln as in the form shown in Figs. 4 and 5, and a centrally arranged pipe 96 extends longitudinally of the kiln and provides means for projecting moisture into the space between the piles of lumber 95. 97 are the steam radiators which 40 are provided with suitable piping for steam supply and drainage. Opposite each of the radiators 97, is arranged an independently operated fan 98, whereby air is made to circulate through the radiators and upwardly 45 through the space between the piles of lumber. Concave deflecting plates 99 are provided for deflecting the drying medium upwardly.

50 The operations of the several forms of my invention are quite similar; and, for clearness and briefness of description, I will refer only to the operation of the form shown in Figs. 1 to 3, inclusive.

55 When the blowers 34 are set in operation, currents of air will be drawn through the ports 33 into the return ducts 18 and discharged into the delivery duct 16, through the openings 30 in the wall 17 thereof; 60 through the radiators 32 and upwardly through the central space 15, where it will pass the recording thermometer bulb 41 and the thermostatic regulator bulb 42 of the thermostatic temperature control. Inasmuch as the baffle curtains 27 prevent the

drying medium from passing over the top of the piles 26, it will be obliged to pass between the layers of lumber and out at the lateral, outside surface of each pile. After the fans have been started, the valve 46 is 70 operated to admit steam into the return ducts 18 through the open tees 44 thereby properly humidifying the drying medium. As the drying medium is being forced along through the delivery duct 16, the deflectors 75 31, arranged in front of the openings 30, will apportion an equal amount of drying medium for each of these openings 30 and thereby cause an even distribution of the medium. The passage up through the central space between the piles of lumber will be very rapid; and, as the drying medium passes between the layers of material, it exchanges a portion of its heat for the moisture of the material. This exchange tends 80 to reduce the temperature and increase the humidity of the drying medium as it passes from one side of the pile of lumber to the other. However, the movement of the drying medium in my kiln is so rapid and uniform at all points in the drying chamber that this tendency is reduced to practically a minimum. In my kiln, therefore, the material is dried at the same rate at the outer edges of the piles as at the inner edges 85 thereof. This not only results in a great saving of time, but produces the greatest possible uniformity of finished product 90 which is of the highest quality. As the drying medium comes from the outer edges 95 of the piles of lumber, it contacts with the porous de-humidifiers 50, which, being of fabric, extract a predetermined amount of vapor from the drying medium without allowing an appreciable amount thereof to escape from the kiln. This feature permits 100 of a very efficient and economical operation. The vapor which passes through the porous de-humidifiers 50, enters the fresh air passageway 52, and mixes with the air contained therein, after which it is removed 105 from the passageway by the constant circulation of fresh air therethrough.

110 As the drying medium is de-humidified by the porous de-humidifiers 50, it is slightly cooled by contact with the de-humidifier. This cooling renders the medium heavier, causing it to fall toward the ports 33 in the return ducts 18. This movement adds appreciably to the velocity and uniformity of 115 flow of the drying medium, since this effect is in the direction of the forced circulation. Due to the combined action of the blowers 34 and the cooling effect of the medium, just referred to, the de-humidified drying 120 medium is drawn downwardly with great velocity and through the openings 33. Thence it is conducted through the return duct 18 and again forced into the delivery 125 duct 16 by the blowers. It will thus be seen 130

that in the operation of my kiln the drying medium is constantly recirculated, the only loss being that of a slight amount of heat due to the contact of the medium with the 5 de-humidifiers 50 as the surplus moisture is being taken from the medium. This makes the operation of my kiln highly efficient as well as economical. Moreover, the operation of my kiln is entirely independent of outside 10 atmospheric conditions. During the drying of some materials, fumes and gases are given off which may be detrimental to the drying process. The de-humidifiers 50, being porous, allow these gases and fumes to 15 pass therethrough and into the fresh air passageways 52 without permitting any appreciable amount of drying medium to escape. By this means the drying medium is kept pure, and the drying operation is not retarded by the presence of any detrimental 20 fumes or gases.

While I have shown and described my device as used in connection with the drying of lumber, it is obvious that it is equally 25 efficient in the drying of many other materials, and that, therefore, the specific arrangement and location of parts may be varied as required to meet different conditions. In the drawings, I have shown an 30 arrangement for accommodating two piles of work-pieces, each adjacent to the other and with a space therebetween. While this is the preferable form of my invention, clearly, only one pile of work-pieces may 35 be provided for.

These and other modifications of the details herein shown and described may be made without departing from the spirit of my invention or the scope of the appended 40 claims; and I do not, therefore, wish to be limited to the exact embodiment herein shown and described, the form described being merely a preferred embodiment thereof.

Having thus described my invention, 45 what I claim is:

1. A drying kiln comprising non-porous kiln walls, and porous de-humidifiers, located in spaced relation with the kiln walls.
2. A drying kiln comprising non-porous 50 kiln walls, porous de-humidifiers, located in spaced relation with the walls, and a plurality of heating units, located below the work-piece.
3. A drying kiln comprising non-porous 55 kiln walls, porous dehumidifiers, located in spaced relation with the walls, a plurality of heating units, located below the work-pieces, and means for forcing air through the heating units.
- 60 4. A drying kiln comprising non-porous kiln walls, porous de-humidifiers, located in spaced relation with the walls, a plurality of heating units, located below the work-pieces, means for forcing air through the heating units and toward the center of the 65

space below such work-pieces, and means for directing the air upwardly and centrally within the kiln.

5. A drying kiln comprising non-porous kiln walls, porous de-humidifiers, located in 70 spaced relation with the walls, heating means, located below the work-pieces, and the work-pieces being so arranged as to provide an open, central space through which the heated air rises. 75

6. In a drying kiln, the combination with work-pieces arranged in adjacent piles, having a central space therebetween, of non-porous walls, porous dehumidifiers in spaced 80 relation with the walls, and a plurality of heating units, located below the piles of work-pieces. 85

7. In a drying kiln, the combination with work-pieces arranged in adjacent piles, having a central space therebetween, of non-porous walls, porous dehumidifiers in spaced 90 relation with the walls, a plurality of heating units, located below the piles of work-pieces, and deflecting plates depending from the top of the kiln and extending downwardly below the top of, and in contact with, one edge of each of the piles of work-pieces. 95

8. In a drying kiln, the combination with work-pieces arranged in interspaced relation with each other and stacked in adjacent piles, having a central space therebetween, of non-porous walls, porous dehumidifiers in spaced relation with the walls, and a plurality 100 of heating units, located below the piles of work-pieces. 105

9. A drying kiln comprising non-porous kiln walls, porous de-humidifiers, located in spaced relation with the walls, and means 110 for humidifying the air. 110

10. A drying kiln comprising non-porous walls, one or more porous de-humidifiers in spaced relation with the walls, means for directing outside air into the space formed between the walls and the de-humidifiers, the walls of the kiln shutting off the atmosphere from the drying space except as it may pass through the pores of the de-humidifiers, and heating means located in the 115 space below the work-pieces. 115

11. In a drying kiln, the combination with work-pieces arranged in interspaced relation with each other and stacked in piles, of a plurality of heating units located below each pile of work-pieces, and means for forcing and recirculating air from a plurality of points through the heating units. 120

12. In a drying kiln, the combination with work-pieces arranged in interspaced relation with each other and stacked in piles, of a plurality of heating units located below each pile of work-pieces, means for forcing air from a plurality of points through the heating units, deflecting plates depending from the top of the kiln and extending down be- 125 130

- low the top of, and in contact with, one of the edges of each of the piles of work-pieces.
13. In a drying kiln, the combination with work-pieces arranged in interspaced relation with each other and stacked in piles, of a plurality of heating units located below each pile of work-pieces, means for forcing air from a plurality of points through the heating units, baffle plates depending from the top of the kiln and extending down below the top of, and in contact with, one of the edges of each of the piles of work-pieces, and means for directing the air upwardly along the side of the piles of work-pieces, having the baffle plates, whereby the air will be passed into intimate contact with the work-pieces.
14. In a drying kiln, the combination with work-pieces arranged in interspaced relation with each other and stacked in piles, of non-porous walls for the kiln, porous de-humidifiers in spaced relation with the walls, and heating units located below the piles of work-pieces.
15. In a drying kiln, the combination with work-pieces arranged in interspaced relation with each other and stacked in piles, of non-porous walls for the kiln, porous de-humidifiers in spaced relation with the walls, heating units located below the piles of work-pieces, and means for forcing air from a plurality of points through the heating units.
16. In a drying kiln, the combination with work-pieces arranged in interspaced relation with each other and stacked in piles, of non-porous walls for the kiln, porous de-humidifiers in spaced relation with the walls, heating units located below the piles of work-pieces, means for forcing air from a plurality of points through the heating units, and means for directing the air upwardly along one side of the piles of work-pieces.
17. A drying kiln formed with a drying chamber, comprising dehumidifiers, inclosing the drying chamber and forming fresh air passageways between them and the outer walls of the kiln, fresh air ducts, having openings communicating with the fresh air spaces, the kiln being formed with a central space, heating units arranged in the central space, the kiln being also formed, below the work-pieces, with delivery ducts and with inlet ducts, the inlet ducts being in open communication with the interior of the kiln, along a point substantially adjacent to the de-humidifiers, and the delivery ducts being in open communication with the central space of the kiln, and means for drawing the air from the return duct and forcing it into the delivery duct.
18. A drying kiln formed with a drying chamber, comprising de-humidifiers, inclosing the drying chamber and forming fresh air passageways between them and the outer walls of the kiln, fresh air ducts, having openings communicating with the fresh air spaces, the kiln being formed with a central space, heating units arranged in the central space, the kiln being also formed, below the work-pieces, with delivery ducts and with inlet ducts, the inlet ducts being in open communication with the interior of the kiln, along a point substantially adjacent to the de-humidifiers, the wall of the delivery duct, adjacent the central space of the kiln, being formed with a plurality of openings, deflector plates for controlling the effective area of such openings, and means for drawing air from the return duct and forcing it into the delivery duct.
19. A drying kiln comprising non-porous kiln walls, porous de-humidifiers, located in spaced relation with the walls, and a plurality of heating units.
20. A drying kiln comprising a floor, a false floor, the floors being in interspaced relation with each other, duct walls connecting the floors, whereby delivery and return ducts are formed, the false floor being formed with a plurality of air openings therethrough, means for forcing air through the ducts and air openings, and means for heating the air.
21. In a drying kiln, the combination of work-pieces arranged in adjacent piles, having a central space therebetween, of two kiln floors arranged in spaced relation with each other, duct walls connecting the floors, whereby delivery and return ducts are formed, the upper floor being formed with openings therethrough, means for forcing air through the ducts and the openings, and means for heating the air.
22. In a drying kiln, the combination with work-pieces arranged in interspaced relation with each other and stacked in adjacent piles, having a central space therebetween, of two kiln floors arranged in spaced relation with each other, duct walls connecting the floors, whereby delivery and return ducts are formed, the upper floor being formed with openings therethrough, means for forcing air through the ducts and the openings, and means for heating the air.

In testimony whereof, I have hereunto signed my name.

CLIFFORD A. CUTLER.
